US00D364609S

United States Patent [19]

Sanchez et al.

[11] Patent Number: Des. 364,609

[45] Date of Patent: **Nov. 28, 1995

[54] COMPUTER INPUT DEVICE

[75] Inventors: **Russell Sanchez; Steven T. Kaneko; Bridget Greenberg; Mike M. Paull**, all of Seattle, Wash.; **Robert Dillon**, Portland, Oreg.

[73] Assignee: **Microsoft Corporation**, Redmond, Wash.

[**] Term: **14 Years**

[21] Appl. No.: **23,097**

[22] Filed: **May 18, 1994**

[52] U.S. Cl. **D14/114**

[58] Field of Search **D14/100, 114, D14/116; D19/41-51; 235/375, 378, 385, 454, 462, 472, 486; 354/80-82; 382/58-69; 250/203.1, 216, 566, 568; D26/37, 45, 50**

[57] CLAIM

The ornamental design for a computer input device, as shown and described.

DESCRIPTION

FIG. 1 is a front isometric view of a computer input device showing our new design;

FIG. 2 is a top plan view thereof;

FIG. 3 is a right side elevational view thereof, the left side elevational view is a mirror image;

FIG. 4 is a bottom plan view thereof;

FIG. 5 is a front elevational view thereof;

FIG. 6 is a rear elevational view thereof;

FIG. 7 is a front isometric view of a second embodiment of the computer input device of FIG. 1;

FIG. 8 is a top plan view of the second embodiment;

FIG. 9 is a right side elevational view of the second embodiment, the left side elevational view is a mirror image;

FIG. 10 is a bottom plan view of the second embodiment; FIG. 11 is a front elevational view of the second embodiment; and,

FIG. 12 is a rear elevational view of the second embodiment.
